United States Patent Office

Des. 177,670
Patented May 15, 1958

177,670

FLOAT

Andrew Glaves, Milwaukee, Wis.

Application April 1, 1950, Serial No. 3,927

Term of patent 14 years

(Cl. D71—1)

Fig. 1

Fig. 2

Fig. 3

Fig. 4

Fig. 1 is a perspective view of a float showing my new design.

Fig. 2 is a top plan view of the float illustrated in Fig. 1.

Fig. 3 is an end view of the float.

Fig. 4 is a front elevational view.

I claim:

The ornamental design for a float, as shown.
